UNITED STATES PATENT OFFICE.

WILLIAM G. HOUSKEEPER, OF NEW YORK, N. Y., ASSIGNEE TO WESTERN ELECTRIC COMPANY, INCORPORATED, OF NEW YORK, N. Y., A CORPORATION OF NEW YORK.

ELECTRON-DISCHARGE DEVICE.

Application filed July 21, 1922. Serial No. 576,462.

To all whom it may concern:

Be it known that I, WILLIAM G. Hous-
KEEPER, a citizen of the United States, re-
siding at New York, in the county of New
5 York, State of New York, have invented
certain new and useful Improvements in
Electron-Discharge Devices, of which the
following is a full, clear, concise, and exact
description.

10 This invention relates to electron dis-
charge devices and to methods of manufac-
turing them.

In electron discharge devices of the ex-
terior anode type, it has heretofore been
15 customary to provide the inner end of the
cathode-grid assembly with a disc of in-
sulating material, the periphery of which
engages the inner surface of the anode to
center the cathode and grid with respect to
20 the anode. When extremely high voltages
are applied to tubes of this character it is
found that the insulating disc breaks down
and allows leakage between the electrodes.

An object of the invention is an electron
25 discharge device of the exterior anode type
wherein the need for a centering disc is
eliminated.

Another object of the invention is a means
for centering an electrode assembly within
30 the vessel of an electron discharge device.

Another object of the invention is a method of arranging the cathode and grid
35 assembly within the anode so that it is co-
axial therewith and spaced therefrom.

Referring now to the drawings, Fig. 1
discloses the stem with the cathode and grid
assembly mounted thereon being inserted
40 within the inclosing vessel. Fig. 2 illus-
trates the fusing together of the flare and
the glass portion of the inclosing vessel.
Figure 3 is a detail view of a portion of the
anode.

The inclosing vessel comprises a tubular
metallic portion 10 to which is fused a glass
45 portion 11, to the outer end of which is
fused the flare 12 of the stem 13. On the
stem 13 is a collar 14 from which is sup-
ported a disc 15 of insulating material, and
50 a second disc 16 of insulating material is
supported from the disc 15, a grid and
cathode assembly of substantially cylind-
rical configuration being supported be-
tween the discs 15 and 16. The discs 15
55 and 16 are provided with center apertures
which are in alignment with a glass tube

17 extending outwardly through the stem
13. The inner end of the anode 10 is closed
by means of cap 10^a which is provided with
a centrally arranged tapped socket.

In the assembly of this device a rod 18
having a threaded end is inserted within the
containing vessel and is screwed into the
socket at the end of the anode. The stem
and electrode assembly are then slid over
the rod 18 which passes through the aper-
60 tures in the discs 15 and 16 through the tube
17. The stem is moved inwardly until the
flare 12 engages the outer end of the glass
portion 11. By virtue of the position of
the rod within the anode 10 the disc 16 is
65 arranged concentrically of the anode 10 and
being of considerably smaller diameter is
separated therefrom by a substantial clear-
ance. The flare 12 is now sealed to the glass
portion 15, the heat being supplied from a
70 flame 19. During the sealing operation the
rod 18 maintains the stem substantially con-
centric of the glass portion 11 whereby the
disc 15 is arranged concentrically of the
anode 10. After the flare has been sealed
75 to the portion 11, the rod 18 is unscrewed
to the portion 11, the rod 18 is unscrewed
and withdrawn from the device and the
tube 17 sealed. The vessel may now be ex-
hausted according to the well known man-
80 nner through the tubulation 20 attached to
the device at the time the flare is sealed to
the portion 11.

The socket to receive the end of the rod
18 may be formed in a stud in a cap 10^a
closing the end of the anode 10 as shown
90 in Fig. 1, or may be in an additional mem-
ber 21 arranged near or in contact with the
end of the anode and held in place by an in-
wardly projecting annular shoulder 22 as
95 shown in Fig. 3.

Although this invention has been dis-
closed in connection with an electron dis-
charge device of the exterior anode type,
it is, of course, apparent that it is applica-
ble to devices wherein the anode does not
100 form a portion of the inclosing vessel. It
is furthermore, of course, understood that
various modifications may be made in the
details of construction without in any way
departing from the spirit of the invention
105 as set forth in the accompanying claims.

What is claimed is:

1. An electron discharge device compris-
ing an enclosing vessel having a stem, an
electrode assembly supported from said
110

stem, said assembly comprising apertured discs, a plurality of electrodes supported by the said discs and a socket in the wall of said enclosing vessel, whereby a rod may be 5 passed through the apertures and seated in said socket during the assembly of the device properly to position the electrode assembly within the vessel.

2. An electron discharge device comprising an enclosing vessel having a stem, an electrode assembly supported from said stem and a tubular member extended outwardly from the inner end of said stem, said electrode assembly being provided with 10 apertures and said vessel being provided with a socket whereby a rod may be passed through said tubular member and electrode assembly and seated in said socket properly to position said electrode assembly in said 15 vessel during the manufacture of the device.

3. In an electrode discharge device an enclosing vessel comprising a glass portion and a cup shaped metal portion which serves as the anode of the device, a stem carried by 20 said glass portion, an electrode assembly supported from said stem, a tubular member projecting outwardly from the inner end of said stem, said electrode assembly having apertures and said anode having a socket 25

whereby a rod may be passed through said 30 tubular member and electrode assembly and seated in said socket properly to position the electrode assembly within said anode during the manufacture of the device.

4. The method of positioning an electrode 35 assembly in an electron discharge device comprising an enclosing vessel, a stem for closing one end of said vessel, and electrodes mounted on said stem, said method consisting of concentrically arranging a guiding 40 member within the enclosing vessel and sliding said stem and electrodes along said guiding member into said vessel.

5. The method of positioning an electrode 45 assembly in an electron discharge device comprising an enclosing vessel, and electrodes mounted on a stem having a passage-way through said electrodes and stem, said method comprising arranging a guiding 50 member concentrically within said vessel 50 and introducing said stem and electrode assembly into said vessel by sliding said assembly over said guiding member, sealing said stem to said vessel and removing said guiding member.

In witness whereof, I hereunto subscribe my name this 18th day of July, A. D. 1922.

WILLIAM G. HOUSEKEEPER.
